UNITED STATES PATENT OFFICE.

FRANCIS MEISEL, OF BOSTON, MASSACHUSETTS, ASSIGNOR TO THE KIDDER PRESS COMPANY, OF WEST VIRGINIA.

INKING APPARATUS FOR PRINTING-PRESSES.

SPECIFICATION forming part of Letters Patent No. 677,877, dated July 9, 1901.

Original application filed April 16, 1900, Serial No. 13,041. Divided and this application filed August 28, 1900. Serial No. 28,277. (No model.)

To all whom it may concern:

Be it known that I, FRANCIS MEISEL, a citizen of the United States, residing at Boston, in the county of Suffolk and State of Massachusetts, have invented a new and useful Inking Apparatus for Printing-PresSES, of which the following is a specification.

This invention relates to an inking apparatus for printing-presSES which has been especially designed for inking flat forms of type; and the especial object of this invention is to provide a simple, efficient, and reliable form of inking apparatus which may be adjusted to ink the forms of type with one or two colors of ink, as desired.

To this end this invention consists of the parts and combinations of parts as hereinafter described.

In a prior application for patent filed April 16, 1900, Serial No. 13,041, of which application the present case is a division, I have shown, described, and claimed a combined box-blank printing and scoring machine to which I have applied my inking apparatus in practice.

In the present application I have shown only such parts as may be necessary to an understanding of the inking apparatus itself.

In the accompanying drawings, Figure 1 is a diagrammatic sectional view illustrating an inking apparatus constructed according to this invention, the operating connections for the printing-press bed and for the form-rollers being omitted for the sake of clearness; and Fig. 2 is a fragmentary perspective view illustrating a portion of the tracks or ways upon which the form-rollers may be supported.

Referring to the drawings and in detail, 12 designates a press-bed, which may be raised or operated by links 13 in any ordinary or well-known manner. Mounted on the press-bed 12 are flat forms of type F and F'. For inking the forms F and F' two separate ink-fountains B and R are employed. When it is desired to employ one color of ink for inking one form and a different color for inking the second form, black ink, for example, may be placed in the ink-fountain B and red ink placed in the ink-fountain R. Coöoperating

with the fountain-roller of the fountain B is a 50 ductor 60 for carrying ink to a distributing-roller 61, which supplies ink to a drum 63 by means of a composition roller 62. By means of this arrangement black ink will normally be carried to the distributing-drum 63. Mounted 55 at the side of the distributing-drum 63 is a second distributing-drum 66, which is normally disconnected with and not supplied with ink from the fountain B. Coöoperating with the drums 63 and 66 are sets of form-rollers 64 60 and 65. The form-rollers 64 and 65 are dropped down into engagement with the distributing-drums 63 and 66, respectively, and are carried back and forth over the forms by any of the ordinary operating connections. 65

In practice the form-rollers 64 are supported upon a set of tracks or ways and the form-rollers 65 are supported on separate tracks or ways, as most clearly illustrated in Fig. 2. The tracks or ways, which support both sets 70 of form-rollers, are preferably operated by any suitable form of connection for raising and lowering the same—such, for example, as the connection shown in United States Letters Patent No. 514,563, granted to myself 75 and Herbert L. Chapin February 13, 1894—so that the form-rollers 64 and 65 will be raised and lowered at proper times, so that the form-rollers 64 will be brought into contact with the form F' and the other set of 80 form-rollers 65 will be brought into contact with the form F. Various other means can be devised, however, for shifting and for raising and lowering the form-rollers, and such connections form no part of my present invention and are not specifically claimed herein. 85

At the opposite end of the press-bed the ink from the fountain R will be taken by a ductor-roll 70 to a distributing-roller 71, which conveys ink to a distributing-drum 73 by 90 means of a composition roller 72. A second distributing-drum 76 is arranged at the side of the distributing-drum 73 to coöperate with the form-rollers 64. By means of this construction it will be seen that red ink will be 95 supplied to the form-roller 65, while black ink will be supplied to the form-roller 64, the drums 66 and 76 simply serving to store sup-

plies of ink and spread the same upon their respective form-rollers at opposite ends of the press.

Whenever it is desired to use ink of one color for both forms, both distributing-drums at each end of the press may be supplied with ink from the fountain adjacent thereto—that is to say, by inserting a composition roller 660 in the position indicated in dotted lines 5 the fountain B will be connected to supply ink to both drums 63 and 66, and in a similar manner by inserting a composition roller 760 the ink-fountain R will supply ink to both drums 73 and 76. By means of this construction 10 it will therefore be seen that I have provided an extremely simple and efficient form of inking apparatus, which may be adjusted to supply forms of type with ink of one color or with inks of two distinct colors, as desired. 15

20 I am aware that numerous changes may be made in the arrangement and proportions of my inking apparatus for printing-presses, and I do not wish, therefore, to be limited to the form of construction herein shown and 25 described; but

What I do claim, and desire to secure by Letters Patent of the United States, is—

1. In an inking apparatus for flat-bed printing-presses, the combination of ink-fountains 30 at opposite ends of the press-bed, a pair of ink-drums located in proximity to each of said ink-fountains, two sets of form-rollers, and distributing connections for carrying ink from each ink-fountain to one or both of the 35 ink-drums located in proximity thereto, whereby the forms may be inked with one or two colors as desired, substantially as described.

2. In an inking apparatus for flat-bed printing-presses, the combination of ink-fountains 40 located at opposite ends of the press-bed, a pair of ink-drums located in proximity to each

ink-fountain, two sets of form-rollers, and distributing connections, comprising removable distributing-rolls arranged so that each 45 ink-fountain may supply ink to one or both of its ink-drums, whereby the forms may be inked with one or two colors as desired, substantially as described.

3. In an inking apparatus for flat-bed printing-presses, the combination of an ink-fountain, a pair of ink-drums located in proximity to each ink-fountain, two sets of form-rollers, and distributing connections for carrying ink 50 from the ink-fountain to one or both of the ink-drums, comprising a ductor-roller, an inking-roller supplied therefrom, and two distributing-rollers for transferring ink from said inking-roller to said ink-drums, one of said distributing-rollers being removable so 55 that ink may be supplied from the fountain to but one of its ink-drums when desired, substantially as described.

4. In an inking apparatus for flat-bed printing-presses, the combination of ink-fountains 60 located at opposite ends of the press, a pair of ink-drums located in proximity to each ink-fountain, two sets of form-rollers, and distributing connections coöperating with each ink-drum, and comprising a ductor-roller, an 65 inking-roller supplied therefrom, distributing-rollers for transferring ink from the inking-roller to the ink-drums, one of said distributing-rollers being removable so that each fountain may supply ink to one or both of its 70 ink-drums as desired, substantially as described.

In testimony whereof I have hereunto set my hand in the presence of two subscribing witnesses.

FRANCIS MEISEL.
